[57] CLAIM

The ornamental design for a set of educational block tiles, as shown and described.

DESCRIPTION

FIG. 1 is a front elevational view of a set of educational block tiles, showing my new design, the rear being plain and unornamented;

FIG. 2 is a top plan view of a single tile thereof, the bottom being identical; and,

FIG. 3 is a side elevational view thereof, the other side being identical.

FIG. 1**FIG. 2****FIG. 3**
